US00D777766S

(12) **United States Design Patent** (10) Patent No.: **US D777,766 S**
(45) Date of Patent: **** Jan. 31, 2017**

(54) **DISPLAY WITH A GRAPHICAL USER INTERFACE**

(71) Applicant: **MITSUBISHI ELECTRIC CORPORATION**, Tokyo (JP)

(72) Inventors: **Satoshi Yamazaki**, Tokyo (JP); **Ayako Nagata**, Tokyo (JP)

(73) Assignee: **Mitsubishi Electric Corporation**, Tokyo (JP)

(**) Term: **15 Years**

(21) Appl. No.: **29/569,907**

(22) Filed: **Jul. 1, 2016**

Related U.S. Application Data

(62) Division of application No. 29/511,457, filed on Dec. 10, 2014.

(57) **CLAIM**

The ornamental design for a display with a graphical user interface, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front view of a display with a graphical user interface of a first embodiment thereof; and,
FIG. 2 is a front view of a display with a graphical user interface of a second embodiment thereof.

The broken lines shown in the figures illustrate portions of the display with a graphical user interface and form no part of the claimed design.
